UNITED STATES PATENT OFFICE.

ALEXANDER H. MORROW, OF PITTSBURGH, PENNSYLVANIA.

BOILER OR HEATER.

1,085,754.

Specification of Letters Patent.

Patented Feb. 3, 1914.

Application filed May 10, 1911. Serial No. 626,353.

To all whom it may concern:

Be it known that I, ALEXANDER H. MORROW, a resident of Pittsburgh, in the county of Allegheny and State of Pennsylvania, have invented a new and useful Improvement in Boilers or Heaters, of which the following is a full, clear, and exact description, reference being had to the accompanying drawings, forming part of this specification, in which—

Figure 1 is a view partly in side elevation and partly in vertical section, showing my invention applied to one type of boiler or heater; Fig. 2 is a section on the irregular line II—II of Fig. 1; Fig. 3 is a view similar to Fig. 1, but showing the invention applied to a different form of boiler or heater; Figs. 4, 5, 6 and 7 are sections taken, respectively, on the lines IV—IV, V—V, VI—VI and VII—VII of Fig. 3; and Figs. 8 and 9 are detail sectional views showing another modification.

My invention has relation to boilers or heaters, and is designed to provide means of novel character for getting the gas into the boiler or heater. The invention is applicable to boilers and heaters of various types, including those which are adapted to burn gas only, and also those which are particularly adapted to burn solid fuel, but which by my invention are adapted to also burn gas.

The nature of my invention will be best understood by reference to the accompanying drawings, in which I have shown its application to several different forms of boilers or heaters and which will now be described, it being premised, however, that the types of heaters shown in the drawings are illustrative only, and that the invention is also applicable to various other types.

Figs. 1 and 2 show my invention applied to a water heater or boiler of the sectional unit type and which is provided with a grate 2 for burning solid fuel. 3 designates one of the sections or units which is provided with a plurality of water spaces 4, the circulating flues 5 for the products of combustion and the depending water legs 6. In accordance with my invention, each of the water legs 6 is divided to form a gas combustion chamber or pocket 7, which is open at its sides and

which also has openings 8, at its top at each side of the relatively narrow web portions 9, for the escape of the products of combustion to the circulating flues of the section. Units 55 or sections of the general character shown in this drawing are well known in the art and need not be specifically described, my invention relating solely to the provision of the combustion chamber or pockets 7, in the depending water legs and to the manner of introducing the gas thereto. For the purpose of introducing the gas into these chambers or pockets, I provide the lower end portion of each of the legs 6 with a plurality of vertical mixing tubes 10, open at their upper and lower ends, their upper ends discharging through the floor of the chamber or pocket, and their lower ends opening through the bottom of the water legs. 11 70 designates gas supply pipes which extend underneath the mixing tubes 10, and are provided with a gas discharge 12, immediately below the lower end of each tube 10, sufficient space being provided adjacent to the 75 discharges for the entrance of air into the tubes with the gas. The amount of air entering these flues with the gas can be regulated at will by raising or lowering the pipes 11, in any suitable manner, one such means 80 of adjustment being hereinafter described.

The operation will be readily understood. When it is desired to use the heater as a gas-fired heater, gas is turned on in the pipes 11, and escaping from the discharges 12, passes 85 upwardly through the mixing tubes 10, of each of the units or sections where it is mixed with the proper amount of air and is discharged into the combustion chambers or pockets where combustion takes place. The 90 products of combustion escape through the openings 8 at the upper ends of the chambers or pockets, at each side of the web portions 9, and thence follow the usual back and forth circulation through the flues or openings 5. When the heater is used with solid fuel, the upper ends of the mixer tubes may be closed in any suitable manner, as by using thin metal covering strips, to prevent cold air entering through these tubes and also to 100 prevent their becoming choked or clogged. The front sections of the heater may be pro-

vided with doors for closing the front sides of their combustion chambers or pockets. When burning gas, the grate may be covered in any suitable manner.

5 In Figs. 3 to 7, inclusive, I have shown my invention applied to a sectional unit heater, which is intended to be fired by gas only. In this type of heater, each sectional unit has a plurality of vertical water legs 13, at 10 its lower portion separated from each other by the combustion chambers or pockets 14, the legs 13 being connected by the lower water space or chamber 15. Extending vertically through this lower water space or 15 chamber are a series of vertical mixer tubes 16, similar to the tubes 10, before described, and supplied by means of the series of gas pipes 17, which are similar to the pipes 11. In Fig. 6, I have shown means for adjustably securing these tubes, consisting of 20 hanger rods 18, seated in legs 19 on the front and back heater sections and having adjusting nuts 20. These pipes may, however, be adjustably secured in any desired manner.

25 Figs. 8 and 9 illustrate the application of my invention to a boiler or heater of circular form. In applying my invention to a heater of this type, the lower vertical water leg is separated into two parts by an intermediate combustion chamber or pocket 21, which is supplied by a series of mixer tubes 22, similar to the device before described.

The mixer tubes may be cast integrally with the heater or heater sections, as shown 35 in the drawings, or they may, of course, be formed separately and suitably secured in place. The form of my invention shown in Figs. 1 and 2 provides a more simple and 40 efficient construction, whereby a boiler or heater primarily intended for solid fuel is also capable of use with gas, the gas being introduced and burned in a manner to give an efficient heating action. In the other forms shown, the provision of the mixer 45 tubes, as described, provides simple means for introducing the gas at the desired points and getting a good distribution thereof within the heater. By the use of such tubes, a number of combustion chambers or 50 pockets may be increased to any desired extent, thus providing a large area of direct water-heating surface and enabling the body of water to be broken up into a considerable 55 number of smaller bodies.

55 It will be noted that the lower portions of the combustion chambers 7 and 14 are at an angle to the upper portion of the chambers, this being for the purpose of providing inclined baffling walls for the gas and 60 air issuing from the mixer tube.

It will be seen that it is immaterial to my invention whether there be employed a single continuous, water-enclosed combustion chamber, as in Figs. 8 and 9, or whether the 65 chamber be divided into a plurality of parts

as in the other figures. By the term "combustion chamber" as used herein and in the appended claims, I mean either a continuous chamber or a chamber composed of a plurality of separate parts or units.

It will be obvious that my invention is, in general, independent of any particular construction of the heater, as a whole, and that it may be applied to a large variety of heaters or boilers.

75 I claim:

1. A heater or boiler having a combustion chamber inclosed within the water space of the heater or boiler and surrounded by such space at its top, bottom and sides, and a relatively small Bunsen tube extending upwardly through the bottom water space into the lower portion of said chamber and said tube being surrounded by the water space; substantially as described.

80 2. A heater or boiler having a combustion chamber inclosed within the water space of the heater or boiler and surrounded by such space at its top, bottom and sides, and a relatively small Bunsen tube extending upwardly through the bottom water space into the lower portion of said chamber and said tube being surrounded by said space, together with means for controlling the amount of air which enters said tube; substantially as described.

85 3. A heater or boiler having a combustion chamber inclosed in the water space thereof, and substantially surrounded by water at its top, bottom and sides, and a plurality of 90 relatively small Bunsen tubes extending upwardly through the water space into the lower portion of said chamber and the said tubes being surrounded by said space and permitting a relatively free circulation of 95 the water through said space; substantially as described.

100 4. A heater or boiler having a water leg formed with a combustion chamber therein, said chamber being surrounded at its top, bottom and sides by the water space of the leg, and a gas mixing tube extending upwardly through the lower portion of the water space into the lower portion of said chamber, said tube being surrounded by the 110 water space to permit a relatively free circulation of the water through said space; substantially as described.

115 5. A heater or boiler having a combustion chamber located in the water space thereof, and substantially surrounded at top, bottom and both sides by such space, a plurality of Bunsen tubes extending upwardly into said chamber, and a series of horizontal back and forth circulating and heating flues with 125 which the combustion chamber communicates at its upper end; substantially as described.

130 6. A heater or boiler having a combustion chamber located in the water space thereof,

and substantially surrounded at top, bottom and both sides by such space, a plurality of Bunsen tubes extending upwardly through the lower portion of the water space and 5 opening into said chamber, and a series of horizontal back and forth circulating and heating flues with which the combustion chamber communicates at its upper end, said circulating and heating flues being also sur-

rounded by water spaces; substantially as 10 described.

In testimony whereof, I have hereunto set my hand.

ALEXANDER H. MORROW.
